(57) **CLAIM**

The ornamental design for a handle light for grilling appliances, as shown and described.

DESCRIPTION

FIG. 1 is an elevated perspective view of the handle light for grilling appliances of my claimed design;

FIG. 2 is a front view thereof;

FIG. 3 is a back view thereof;

FIG. 4 is a top view thereof;

FIG. 5 is a bottom view thereof;

FIG. 6 is a left side view thereof;

FIG. 7 is a right side view thereof; and,

FIG. 8 is an elevated perspective view thereof, shown in an environment of use.

The broken lines in FIG. 8 showing the handle of a grilling appliance represent environmental structure and do not form any part of the claimed design. The broken lines in FIG. 5 depict portions of the handle light for grilling appliances and form no part of the claimed design.
